UNITED STATES PATENT OFFICE

JOE M. LUNZ, OF FORD, KANSAS

CHAFFER

Application filed February 16, 1927, Serial No. 168,755. Renewed March 23, 1930.

This invention relates to threshing machines and more particularly to separators therefor commonly known as "chaffers", and which is designed as an improvement over the separator shown and described in my Patent No. 1,428,599 dated September 12, 1922.

A primary object of the invention is to provide a separator of this character for removing chaff, tailings and the like, which is constructed to meet the various conditions of grain, permitting the strawracks to be made coarser, to be removed entirely or be combined with the chaffers thereby increasing the capacity of the separator from 10 to 25% over the system of separation now employed where an automatic separation is required.

Another object of the invention is to provide a separator having an adjustable blast control which may be automatic or made stationary as desired.

Another object is to provide a separator employing a plurality of sets of chaffers each set being composed of a plurality of screens and which are adjustable to meet various conditions of the grain.

In carrying out these objects, the invention is susceptible of a wide range of modifications without departing from the spirit or sacrificing any of the advantages of the claimed invention; there being shown in the drawings for illustrative purposes a preferred and practical form, in which

Figure 1 represents a longitudinal section of a portion of a threshing machine with this improved separator shown applied;

Fig. 2 is a perspective view of the separator detached;

Fig. 3 is a detail side elevation;

Fig. 4 is a detail perspective view of the blast deflector.

In the embodiment illustrated the chaff and grain separator shown generally at 10 is used in connection with the thresher 1 of conventional type having the usual grain board 9 from which the grain and tailings drop onto the separator 10. This separator is provided at its front end with an extension grain pan 11 designed for conveniently installing the separator on machines of dif-

ferent makes and also provides for a better air control.

The frame of this separator includes side boards 12 and 13 which extend the full length of the shoe 2 and have fixed to their inner faces cleats 12^a arranged in step-like form to support the screens to be described. A screen 36 is located horizontally near the bottom of shoe 2 to receive the grain which passes through the chaffers of the separator and which delivers the screened grain to the conveyor 37 which conducts it out of the machine.

Carried by this frame are two sets of stub chaffers 20 and 30 arranged one in advance of the other and each composed of a plurality of superposed grading screens. Each set comprises three screens, those of set 20 being numbered 21, 22 and 23 while those of set 30 are numbered 31, 32 and 33. These screens may have frames or not, as desired and the screening elements are preferably made of perforated metal sheets. The uppermost screens have larger and fewer perforations while those arranged below have perforations increasing in number and decreasing in size. These screens also extend outwardly in step-like form and are fixed to the cleats 12^a at opposite sides of the separator 10.

The screens of the respective sets have longitudinally arranged spaced cleats 25 and 25^a disposed between them and extending out over the screen below operating as supports for the screens above and forming air passages in which the air is directed straight through the space between the screens in case of a side draft.

The bottom screen 23 of the set 20 has a rearwardly extending hinged perforated extension plate 26 with upstanding end members 27 provided with slots 28 through which bolts 29 pass and engage the side members 12 and 13 for adjustably securing said screen extension 26. This adjustable plate 26 has its rear end overlying the front edge of the uppermost screen 31 of set 30.

The rear lower screen 33 of set 30 has hingedly connected thereto an extension screen 34 provided with upstanding end members 40 slotted as shown at 42 to receive bolts 100

43 for adjustably securing it to upstanding plates 39 mounted on the side boards 12 and 13. The side plates 39 of the chaffer set 30 are also slotted as shown at 45 for the passage of bolts 46 to adjustably fasten set 30 at its front end to the side boards 12 and 13, of the chaffer frame, a series of bolt holes 44 being formed on boards 12 and 13 to provide for this adjustment.

10 A blast deflector 50 is located at the front end of chaffer 30 between it and chaffer 20 and has rearwardly extending slotted links 51 slidably engaged with the cleats 25^a between screens 31 and 32. Links 52 are pivotally connected at one end with the rear ends of links 51 and are apertured at their free ends as shown at 53 to engage with fingers 54 carried by a rod 55 rotatably mounted in a bearing 34^a on the rear end of screen 34.

15 The turning of this rod operates to shift the blast deflector 50 longitudinally of the chaffer. Fixed to one end of the rod 55 which is offset to form a crank arm 55^a is a strap 57 to which is connected a coiled spring 56. An eye-bolt 59 is connected with the other end of said spring and passes loosely through an apertured ear 60 of a bracket 61 secured to the outer face of the side board of shoe 2. This bolt 59 is equipped with a nut 62 for 20 adjusting the tension of the springs, to permit the blast control 50 to operate automatically or to be fixed stationary as may be desired. The crank arm 55 passes through a slot 61^a of bracket 61 to provide for the partial oscillation of the rod and the consequent movement of the deflector 50. It will thus be seen that the blast control 50 is regulated by the tension of the spring 56 the spring operating to give and take as the air of the 25 fan is applied against the deflector 50 according to variations of speed of the machine. This permits the fan doors to be clear open at all times since the second set of drops do not handle the amount of grain, chaff and straw as the front chaffers do. It is, of course, understood that the blast control deflector 50 may be kept stationary, if desired, by adjustment of the nuts and bolts with which the spring is connected.

30 The extension screen plate 34 is designed to receive the short tailings of wheat which do not pass through the stub chaffers and discharge them into the elevator 38 by which they are conveyed back to the cylinder and 35 concave of the thresher.

The same windboard 41 is used in connection with this separator as is shown in my patent above referred to and is adjustable to any desired angle by means of the handle 40 to provide for controlling the blast of air from the fan or blower 40^a.

The use of this improved separator assures separating of all the grain on its first passage through the threshing machine so that 45 nothing but stems, white caps and small par-

ticles such as are not blown out through the chaffer are returned to the cylinder to be threshed again.

Without further description it is thought that the features and advantages of the invention will be readily apparent to those skilled in the art, and it will of course be understood that changes in the form, proportion and minor details of construction may be resorted to, without departing from the spirit or the invention or its scope as claimed.

I claim:

1. In a threshing machine, the combination with a shoe; of a plurality of sets of stub chaffers mounted therein, one in advance of the other and each adjustable independently of the other, and an air blast control connected with one set of said chaffers and located between the sets.

2. In a threshing machine, the combination with a shoe; of a plurality of sets of stub chaffers mounted therein, one in advance of the other and each adjustable independently of the other, and an air blast control located between the sets of chaffers, and means whereby said control may operate automatically by the force of the blast or be held fixed.

3. In a threshing machine, the combination with a shoe; of a plurality of sets of stub chaffers mounted therein one in advance of the other, the screens of each set being arranged in step-like form one above the other, and a perforated extension plate connecting the lowermost screen of one chaffer set with the top screen of the other set.

4. In a threshing machine, the combination with a shoe; of a plurality of sets of stub chaffers mounted therein, one in advance of the other, and each being adjustable independently of the other, and inclined connecting perforated plates between said sets, said chaffers being adapted to be located within the shoe below the top thereof.

5. In a threshing machine, the combination with a shoe; of a plurality of sets of stub chaffers mounted therein one in advance of the other, the screens of each set being arranged in step-like form one above the other, and a perforated extension plate hingedly connected with the lowermost screen of one set and overlying the uppermost screen of the other set, said hingedly connected screen or extension screen being adjustably mounted to vary the inclination thereof.

JOE M. LUNZ.
